APPARATUS AND METHOD FOR SECTIONAL
RADIOGRAPHY

Jean Kieffer, Norwich, Conn.

Application July 20, 1943, Serial No. 495,415

16 Claims. (Cl. 250—61.5)

This invention relates to an apparatus and method for sectional radiography.

Heretofore, sectional radiography has been principally used for making skiagraphs of thin layers or laminae of the human body, known as "laminagraphs." With the exception of equipment wherein the patient is rotated without being shifted bodily, and the film rotated simultaneously about an axis parallel to the axis of rotation of the patient, the X-ray equipment heretofore employed for obtaining laminagraphs required synchronized motion of the X-ray tube and film.

None of this equipment could be used successfully in industrial sectional radiography of inanimate objects, for in the apparatus in which the X-ray tube had to be moved, the huge size and massive weight of the tubes and associated equipment needed greatly hindered synchronous movement. This equipment ordinarily included a high tension transformer which, with the tube, was immersed in an oil tank. The mass of the tube and equipment was so great that any movement thereof placed too great a strain upon the supports, and in addition required too complicated a system of moving heavy duty supports, electric wiring and cooling conduits. On the other hand, in the apparatus in which the object being radiographed was rotated without bodily shifting, it was impossible to blur-eliminate shadows of dense portions of the object immediately above or below the axis of rotation and, in general, in such apparatus dissemination of unwanted shadows by blurring could not be accomplished as widely and uniformly as might be required. The possibility of keeping the tube stationary was suggested in my Letters Patent No. 1,954,321. However, to date, as far as I am aware, and despite the desirability of employing massive X-ray tubes in sectional radiography, no apparatus or method capable of taking clear sectional radiographs with a stationary tube has been developed.

It is, accordingly, an object of the present invention to provide an apparatus and method for sectional radiography wherein an X-ray tube is maintained stationary but the radiographed object and film are so manipulated as to substantially eliminate all undesired shadows.

Sectional radiography of inanimate objects is difficult, since it is not easy to disassociate the shadows of a desired plane portion of an intricate structure from the shadows of the overlying and underlying portions. Ofttimes complex motions of the radiographed object and film are required and I have found that such motions are only effective when both the object and the film are

bodily shifted so that all undesired shadows are uniformly moved and dispersed to the same degree. It is, therefore, a further object of my invention to provide a method and apparatus for sectional radiography wherein both the film and object are bodily shifted, while the tube remains stationary.

In my previous patents, No. 1,954,321, for X-ray device and method of technique; No. 2,167,114, for X-ray device, and No. 2,167,115, for Radiation method and apparatus, wherein the object being radiographed is held stationary and the X-ray tube and X-ray film moved in parallel planes, I have shown a variety of motions for the tube and film, including linear, circular, sinusoidal and spiral. It is a further object of the present invention to provide, in an apparatus wherein the film and radiographed object are bodily shifted and the X-ray tube maintained stationary, various types of bodily movements for the object and film corresponding to those disclosed in the aforesaid patents, so as to enable employment of a movement best suited for obtaining clear sectional radiographs having widely and uniformly dispersed extraneous shadows. For some inanimate objects simple linear bodily translation of the object and film suffices to obtain clear sectional radiographs. More complex objects require a more intricate motion which may include a combination of linear bodily translation and uniform or harmonic bodily movement at an angle to the translation, or bodily shifting in a circular or spiral path either with or without linear translation. The specific motion selected in each case will depend upon the nature of the object being radiographed and the plane whose skiagraph is to be taken.

An additional object of the invention is to provide an apparatus and method which comprises relatively few and simple parts, is rugged and durable in operation, and lends itself readily to a bodily plane movement of an object and film best adapted to take sharp, clear and distinct sectional radiographs.

Still another object of the invention is to provide an apparatus and method of the character described for serial sectional radiography of a plurality of inanimate objects successively scanned by a stationary X-ray tube.

A further object of the invention is to provide an apparatus and method of the character described capable of simultaneously taking a plurality of sectional radiographs of spaced planes of each of a series of inanimate objects successively scanned by a stationary X-ray tube.

Other objects of the invention will in part be obvious and in part hereinafter pointed out.

The invention accordingly consists in the features of construction, combinations of elements, and arrangements of parts which will be exemplified in the constructions hereinafter described, and of which the scope of application will be indicated in the appended claims.

In the description and claims the term "X-ray" 10 connotes, in addition to the conventional definition of a Roentgen ray, any radiation which is capable, after penetrating a substance and being absorbed therein in different degrees, of forming a latent, virtual or real image in a suitable medium.

The terms "film" and "plate" broadly denote such a medium. This medium may be in the usual form of a pellucid carrier through which there are uniformly dispersed particles photo-chemically sensitive to X-rays. Another standard form is a fluorescent screen which is luminously activated by X-rays. In general, therefore, the term "film" or "plate" embraces any medium upon which an image can be optically realized either coincident with impingement of X-rays or 25 subsequent thereto.

The terms "plane movement" and "planar movement" denote movement of a body such that a section thereof travels in a single plane.

The term "in parallel planes" as applied to 30 movement denotes motion of two bodies in such fashion that portions thereof parallel to the direction of motion move parallel to each other.

The terms "bodily" and "bodily shifting" denote movement wherein each element of an object travels parallel to every other element and at the same instantaneous linear speed. Put in another way, if a set of coordinate axes are drawn through any point of the object, these axes do not change their direction as the object bodily shifts. It is to be understood, however, that bodily movement may be combined with other types of movement, as for example, simple rotation.

In the accompanying drawings in which are 45 shown various possible embodiments of the present invention;

Fig. 1 is a side elevational view of an apparatus embodying one form of my invention;

Fig. 2 is a top plan view thereof;

Fig. 3 is a fragmentary oblique view of the 50 plate supporting mount and is illustrative of the means by which the plate can be tilted to secure angled transverse sectional radiographs;

Fig. 4 is a diagram illustrating the principle of 55 operation of the instant invention;

Fig. 5 is an oblique view of an apparatus embodying a modified form of the invention with 60 portions thereof broken away to show constructional details;

Fig. 6 is a schematic side elevational view of 65 another modified form of my invention which is adapted to take sectional radiographs of a series of continuously moving inanimate objects;

Fig. 7 is a top plan view of the apparatus illustrated in Fig. 6; and

Fig. 8 is a schematic drawing of an apparatus 70 embodying yet another modified form of my invention which is adapted to simultaneously take a plurality of radiographs of spaced planes of a series of continuously moving inanimate objects.

In general, I accomplish the basic objects of my invention by providing an X-ray tube which remains stationary during radiographing and two separate supporting means, one for the object

being radiographed and the other for the film. Means is further provided to bodily shift the two supporting means in parallel planes and at such relative speeds that a point in a plane of an object to be sectionally radiographed sweeps past the target of the X-ray tube at the same instantaneous angular speed at which a point on the film moves angularly past the target. By employing a stationary X-ray tube, I do away with the movement thereof, heretofore generally believed necessary to the practice of sectional radiography. With the X-ray tube stationary, the large 30 to 1000 kv. tubes requisite for industrial radiography can be simply mounted, and there is no need for establishing any moving connection between the machine proper and the tube, although the tube and its associated equipment, may themselves be moved. By employing bodily shiftable supporting means for the inanimate object and film, all types of intricate plane motion may be imparted, and that particular motion selected which is best adapted to eliminate, by blurring, all shadows of dense portions of the object above and below the plane to be radiographed.

Referring now to the drawings and more particularly to Figs. 1 through 3, I have there illustrated a simple apparatus 10 which embodies the present invention and in which both the film and object being radiographed are merely bodily translated. Said apparatus comprises a bed 12 supported by legs 14. In the upper surface of the bed are formed two pairs of parallel grooves 16, 18.

The outer pair of grooves 16 serve as tracks to guide the movement of a lead-shielded carriage 20 on which an inanimate object O is supported. Said carriage 20 has a plurality of rollers 22 which ride in the grooves 16. It will be obvious that with this construction the carriage is restricted to bodily movement along a straight line in a plane parallel to the top of the bed 12. The top of the carriage 20 is provided with an aperture 24, in which there is inset a Bakelite panel 26 large enough to support any object desired to be sectionally radiographed.

Beneath the carriage 20 is a second carriage 28, whose top is preferably substantially parallel to that of the first carriage 20. The second carriage 28 is supported on rollers 30 which ride in the grooves 18. In this manner I constrain the movement of the two carriages 20, 28 along parallel straight lines in spaced parallel planes.

The carriage 28 supports a film F, carried in a mounting 32, one end of which is hinged to said carriage. The other end of the mounting is pivotally connected to a link 36 having a longitudinal slot 38. A horizontal screw 40 carried beneath the carriage 28 freely passes through said slot 38, and may be clamped in any position by a wing nut 42. I provide this means for inclining the film F for a purpose hereinafter described. It may be mentioned at this time, however, that when it is desired to substantially tilt the film the Bakelite panel 26 can be lifted out of its aperture 24.

It will be appreciated that, owing to the nature of the supports for the carriages, the object and film F, regardless of the inclination of the film, are only capable of parallel plane movement.

The means for bodily shifting the object carriage 20 and film carriage 28 at their proper relative speeds comprises a heavy link 44 which is rotatably mounted on a pivot 46 supported on a stationary part of the apparatus, such as an

extension 47 on one of the legs 14. Said link 44 has an elongated slot 48 formed therein which is adapted to slidably receive two pins 49, 50. One of these pins 49 is rigidly connected to the film carriage 28 and the other to the object carriage 20. Either of the pins, as for example the pin 50, may be so mounted on its supporting carriage that, although capable of rigid connection therewith, it may be shifted towards and away from the pivot 46. This may be accomplished by providing on the object carriage 20 a depending post 52 of non-circular cross section on which there is slidably mounted a collar 54 having a finger 56 extending in the direction of the link 44 and to which finger the pin 50 is affixed. A butterfly screw 58 in the collar 54 serves to set the pin 50 at any selected distance from the pivot 46. It will be apparent that when the link 44 is oscillated about the pivot 46, the two pins 49, 50, and, therefore, the film and object carriages 28, 20, will move in parallel paths and at relative rates of speeds, which are directly proportional to the distances of said pins from the pivot 46.

The apparatus 10 also includes an X-ray tube 60 mounted in a housing 62 which is rotatably supported in a yoke 64 secured to the end of an arm 66, which is flexibly carried on a post 68 for universal movement in conventional manner. The illustration and description of the X-ray tube and its mount are conventional, and it will be appreciated that the heavier types of X-ray tubes and their companion equipment, such as transformers, may be mounted in any manner well known to the art. It suffices for the purposes of the present invention that the tube is not connected for synchronous movement relative to either carriage 20, 28. It is preferable, however, to have the tube tiltable and to have either the tube or the carriage so mounted that their position may be relatively adjusted for sectionally radiographing transverse planes by the decentering method hereinafter described.

Any suitable means may be employed for moving the link 44, and thus translating the object carriage 20 and film carriage 28. Such means may comprise an electric motor 70 mounted on a leg 14 and having a gear 72 which drives a sector rack 74 on said link 44.

In Fig. 4 I have diagrammatically illustrated the principle upon which the present invention operates. In this figure T represents the emitting target of an X-ray tube, O the inanimate object to be sectionally radiographed, and F the film on which the radiograph is to be visually realized. P represents the plane of the inanimate object O which is to be sectionally radiographed. The film and inanimate object are shown in two positions. The one in full lines represents an early position of the film and object when the entire object is between the target and film. The one in dotted lines denotes the respective positions of the film and object after a period of movement. o indicates a point in the plane of the object which is to be radiographed. Another point q is in the same object O directly beneath the point o. At the time that the film and object are in their initial position, a ray emanating from the target T and passing through the point o will also pass through the point q and strike the film F at a point f. The latent image formed at this instant will thus be the superimposed shadows of the points o and q. When the object and film have moved at predetermined different rates of speed for a period

of time they will reach their dotted line positions. At such time the point f will have moved to f', the point o to o', and the point q to q'. The positions of the points o' and f' are such that a ray emanating from the fixed target T will pass in a straight line through o' and f'. However, a ray passing through the point q' will strike the film at a new point f''. Thus the shadow of the point q' will blur during movement of the film and inanimate object through the respective distances ff', oo'.

It will thus be seen that the relative rates of speed of the object O and film F to secure sectional radiography of said object along a plane P must be so selected that said object and film as they are bodily shifted along parallel spaced planes simultaneously sweep through the same angles about the target T. A more exact method of expressing this same relationship between the target, plane of sectional radiography, and film, is that the triangles formed with the target as the vertex, and the distances travelled of points in the film and selected plane as the bases must be similar. This can be mathematically expressed in the following ratio: $To:Tf:oo':ff'$. It will now be apparent that to sectionally radiograph a plane parallel to the plane P and including the point q, it is necessary to move the inanimate object O through a distance qq'' instead of a distance oo' while the film is moved through a distance ff' . Under these conditions the shadow of the point o on the film F would be blurred. It will also be appreciated that the distances oo' , qq'' and ff' , instead of merely representing space traversed, may denote velocities of travel; that is oo' may represent a certain distance per unit of time, and qq'' and ff' distances for the same unit of time.

Referring back now to Fig. 1, I have there represented the distance along a straight line from the target T of the X-ray tube to the plane P in focus by the reference character A and the distance along the same line from the plane P to the plane of the film F by the reference character B. The distance through which the inanimate object O moves during a given period of time has been represented by the reference character E, and the distance through which the film moves in the same unit of time by the reference character G. From similar triangles the equation governing the relationship between these variables is:

$$\frac{A}{A+B} = \frac{E}{G}$$

To secure relative movement of the inanimate object and film in accordance with this equation, it is merely necessary to set the collar 54 a proper distance away from the pivot 46.

The perpendicular distance from the pivot 46 to the path of movement of the pin 50 for the object carriage 20 is represented by the reference character D and the perpendicular distance between the paths of movement of the object pin 50 and the film pin 49 by the reference character C.

It will be apparent that the object pin 50 moves at the same rate of speed as the object O and the film pin 48 moves at the same rate of speed as the film F. Therefore, when the object has moved a distance E, the object pin 50 will have moved a similar distance E and the film pin 48 a distance G. From similar triangles the equation governing the motion of the link 44 and pins 48 and 50 is:

$$\frac{E}{G} = \frac{D}{C+D}$$

To obtain the relationship between the position of the pins 48 and 50 and the relative spacing between the target T, film F and plane P to be radiographed, the value of

$$\frac{E}{G}$$

secured from either the equation governing the motion of the link 44 or the equation governing the motion of the film and object, is substituted in the other equation. The following equation results:

$$\frac{A}{A+B} = \frac{D}{C+D}$$

Solving for B we have:

$$B = \frac{AC}{D}$$

It may also be desired to secure the relationship between A and B in terms of velocities of the object and film. This may be obtained by solving for B in the equation governing the motion of the film and object,

$$B = A \left(\frac{G}{E} - 1 \right)$$

where G equals the velocity of the film and E, the velocity of the object. This equation is more general as it does not include any variables dependent upon a particular means for moving the film and object.

If a transverse section of an object which is too long for sectional radiography is to be taken, I may arrange the apparatus 10 so as to take a radiograph of the desired plane by employing a "decentering" method. In accordance with this method, the film and object, instead of moving in such manner that the X-rays emanating from the target T have to pass through substantially the entire object, are so arranged that the X-rays need only pass through a portion of the object at an angle to the longitudinal axis thereof. Pursuant to this method, I bolt the elongated object to the carriage 20 at a point spaced from the aperture 24 in which the Bakelite panel 26 is disposed, a plurality of apertures 75 being provided in the carriage for such purpose. In this position the film is disposed to one side of the object. The X-ray housing 62 is swung about the post 68 so that the target lies to the other side of the object. The arm 66 is rotated and the housing 62 turned in the yoke 64 so that X-rays emanating from the target are directed through the portion of the object to be sectionally radiographed and toward the film F. The object and film are then bodily shifted at relative rates of speed satisfying the equation

$$B = A \left(\frac{G}{E} - 1 \right)$$

The foregoing method of decentering may be practiced with the film lying either flat, as indicated in Fig. 1, or tilted, as indicated in Fig. 3. Where the film is horizontal, the transverse plane will also be horizontal, and where the film is tilted, the transverse plane radiographed will be disposed at a like angle, as explained in my said Patent No. 2,167,115.

In Fig. 5 I have shown an apparatus 80 embodying a modified form of my invention with which a wide selection of complex movements may be obtained. Said apparatus comprises a bed 82 supported on legs 84. The bed carries a pair of parallel rails 85 for the rollers 86 of an object-supporting carriage 88. Said carriage may

include longitudinal struts 90 extending generally in the direction of the rails 85 and connected by transverse parallel rails 92. These latter rails serve as tracks for rollers 94 of an object table 96. With this construction it will be apparent that the object table 96 is capable of any planar movement having components parallel to the longitudinal rails 85 and transverse rails 92.

The longitudinal rails 85 also support the rollers 98 of a film carriage 100 comprising struts 102 extending in the general direction of the rails 85. These struts are connected by transverse parallel rails 104 which serve as tracks for the rollers 106 of a carrier 103 for a film F. The film F, like the table 96, is thus capable of any planar movement having components parallel to the longitudinal rails 85 and the transverse rails 104.

Means is provided for insuring movement of the film F and object table 96 at relative rates of speed satisfying the equation

$$B = A \left(\frac{G}{E} - 1 \right)$$

Such means may comprise a linkage system including a shaft 110 universally pivoted to a cross rail 112 by a gimbal 114 pinned to said shaft. Another gimbal 116, slidably received on the upper reach of the shaft, is secured to an arm 118 extending from the film frame 108. Still another gimbal 120 is slidably received on the shaft intermediate the gimbals 114 and 116. This intermediate gimbal is secured to a bar 122 slidably but non-rotatably mounted on a leg 124 pendent from the object table 96. The bar 122 may be held in selected position by means of a wing set screw 126.

Since the film frame 108 and object table 96 move in parallel planes, the ratio of their speeds controlled by the linkage system will be:

$$\frac{E}{G} = \frac{D'}{C' + D'}$$

where D' is the distance between the gimbals 114 and 120 and C' is the distance between the gimbals 116 and 120.

The X-ray tube is not shown in conjunction with the device 80, but it will be understood that the same may be similar to that shown in the first form of my invention. The plane radiographed in any object carried by the table 96 will be determined by the relative positions of the object, target, and film, the angular position of the film and the distances between the three gimbals 114, 116, and 120.

Still further, in accordance with my invention, I provide means for actuating the object table 96 or film frame 108, their relative motion being, of course, controlled by the shaft 110. Such means comprises a motor 128 which, with its associated gear housing 130, is mounted for slideable movement longitudinally of the bed 82 by dovetailed legs (not shown) received in the ways 132 of a plate 134 straddling the legs 84. In the lower end 136 of the gear housing is a variable speed control which drives a sheave 138 whose speed is governed by a lever handle 140. A wire cable 142 is wrapped at least twice about the sheave and has its ends secured to spaced fixed pins 144 pendent from the plate 134. I also provide a reversing mechanism controlled by a lever handle 146 and a clutch mechanism controlled by a lever handle 148. It will be seen that when the sheave is turned it will pull the motor along the plate 134 parallel to the longitudinal rails 85.

In the upper end 150 of the gear housing 130 I provide another variable speed control which drives a shaft 152, whose speed is governed by a lever handle 154. Lever handles 156, 158, respectively, control a reversing mechanism and a clutch mechanism for governing the operation of the shaft. Said shaft 152 is journalled in a bearing 16 slidably mounted by a dovetailed leg 162 in a way 164 of a plate 167 bridging the legs 84. A templet cam 168 similar to that shown in my United States Letters Patent Nos. 2,167,114 and 2,167,116 is loosely mounted on the shaft 152. Said cam has a spiraled groove in its upper surface and is prevented from rotating relative to the drive shaft 152 by pins 169 slidable in a slot 170 in the upper edge of the plate 167. Above the cam 168 a disk 172, keyed to the shaft 152, includes a radial slot 174 and a plurality of radially arranged holes 176 adapted to receive a pin 178. When the pin is placed in a hole, it will not extend into the groove in the cam 168, so that rotation of the disk 172 will cause the pin 178 to travel in a circular path. On the other hand, when the pin is placed in the slot 174, a portion of reduced diameter extends therethrough and is received into the spiral channel of the cam 168, so that rotation of the disk 172 will cause the pin 178 to move in a spiral path governed by the shape of the groove. The construction of a pin adapted to cooperate in the foregoing manner is fully described in my two aforementioned patents. The pin is set into an extension 180 rigidly secured to the table 96, so that any motion imparted to the pin will be transferred to the table and through the shaft 152 to the film frame 108.

It will be appreciated that by manipulation of the various lever handles 136, 146, 148, 154, and 158, an extremely wide variety of motions can be imparted to said pin and in turn to the object 40 and film.

In Figs. 6 and 7 I have schematically illustrated another modified form of apparatus 190 which is specially adapted to secure sectional radiographs of a series of continuously moving inanimate objects. This apparatus, unlike that shown in the earlier described forms of the invention, imparts to both the film and objects motion having a component which continuously proceeds in the same direction, so that there need be no interruption of radiography to restore the supporting and moving parts for the film and object to their initial positions. This may be accomplished, in general, by employing a conveyor belt system for moving objects to and past the X-ray tube and by using spools to move a strip of film beneath the objects.

Referring now in detail to Figs. 6 and 7, the apparatus 190 comprises a pair of side frames 192, 194 which serve as supports for the conveyor belt system and the film system.

The conveyor belt system includes two parallel spaced rollers 196, 198, whose axles 200, 202 are slidably journalled in the side frames 192, 194. One of the axles, for example, 202, is driven by a motor 204 through a chain 205 which engages a pulley 208 slidably keyed to the axle 202 and rotatably but non-shiftably held to the side frame 194. The opposite end of this axle extends beyond the other side frame 192 and carries a fixed collar 210 which rides in the groove 212 of a barrel cam 214 turned through a gear train 216 by another motor 218. The two axles 200, 202 are rigidly connected for unitary transverse shifting by struts 220, whose opposite ends are non-

slidably secured to said axles near the ends of the rollers 196, 198 and which are made rigid by cross bars 222. It will thus be seen that while the conveyor belt 224 is being driven to progressively advance a series of inanimate objects O from the roller 198 to the roller 196, said rollers and belt will be bodily reciprocated transversely of the axles 200, 202 in accordance with a cycle determined by the contour of the cam groove 212.

10 The film system comprises a pair of film spools 226, 228 whose axles 230, 232 are rotatably and slidably journalled in the side frames 192, 194. A helical spring belt 234 connects pulleys 236 and 238 on the roller 198 and take-up spool 228 thereby providing an impositive drive for the film take-up 228. For advancing the strip film S I employ a pair of sprockets 240 which engage perforations P at the sides of said film. These sprockets are driven from the axle 202 through a gear train 242 in which gears are adapted to be replaced in any well known manner to vary the angular speed of the sprockets 240. A conventional drag may be placed upon the axle 230 to which the supply spool 226 is affixed to keep the film taut between said spool and the sprockets 240. The film is maintained taut between the sprockets and the take-up spool 228 by driving the axle 232 faster than the film is moved by the sprockets. The spools 226, 228 and the sprockets 240 are tied together for unitary lateral shifting by struts 244 rotatably but non-slidably secured to the axles 230, 232 and said sprockets and rigidified by cross bars 246.

15 It will now be apparent that owing to the different rates of speed at which the objects O and strip film S pass beneath an X-ray tube 248, a sectional radiograph will be secured of each object O on the conveyor belt 224. The plane of this object will be the one satisfying the equation

$$B = A \left(\frac{G}{E} - 1 \right)$$

20 where A is the distance from the plane in focus to the target of the tube, B the distance from said plane to the film, E the rate of travel of the objects on the conveyor belt, and G the rate of travel of the strip film. It will be appreciated that the gear train 242 must be selected to impart a rate of travel to the film faster than the rate 25 of travel of the conveyor belt.

25 In accordance with another feature of my invention, the film and conveyor belt may be bodily transversely shifted at relative rates of speeds also satisfying the foregoing equation. To this end I may employ a linkage system similar to that shown in the first form of the invention. Said system includes a slotted link 250 pivoted at one end to a side frame 192. At the far end of the slot a pin 252 is received which is secured 30 to the outer race of a ball bearing 254 whose inner race is fixed to the axle 230 of the film spool 226. The top of said pin is headed to prevent it from slipping out of the slot. The inner race of another ball bearing 256 is fixed to the axle 200 of the belt roller 196. The outer race of the latter ball bearing carries an extensible link 258 on whose free end a pin 260 is mounted, which is received in the slot of the link 250 intermediate the pin 254 and the fulcrum of the link. This second pin 260 is also headed to prevent it from slipping out of the slot. A set screw 262 holds the link 258 in any adjusted position.

35 It will be seen from the discussion of the principles governing the operation of the link in the first form of the invention that the pin 260

should be so set that the ratio of the transverse speeds of the film and series of objects will be similar to the ratio of the longitudinal speeds of the film and objects, i. e., G:E. In this manner the transverse as well as the longitudinal movement of the film and objects will cause the same plane to be in focus.

If the objects are of such construction that transverse movement is not required to obtain a clear sectional radiograph, the motor 218 may be stopped.

The film system may be housed in a light-proof casing 264 through which the axles 230, 232 protrude. The top of the housing carries an adjustable lead mask 266 having an aperture 268 which is covered with a panel of Bakelite 270, said aperture lying beneath the X-ray tube 272. The time of exposure for the film is controlled by the rate of travel of the film and the length of the aperture 268 parallel to the direction of film travel between the spools 228, 228. The aperture length can be changed by adjusting the mask 256. By way of example, if the speed of the film past the aperture 268 is one inch per second, and the length of the aperture thirty inches, the period of film exposure will be thirty seconds.

Instead of sectionally radiographing only one plane of a series of continuously moving objects in the manner just described, I may simultaneously sectionally radiograph a plurality of planes and in Fig. 8 I have schematically illustrated an apparatus 280 capable of performing in such manner. The conveyor system of this apparatus is similar to that just described, differing therefrom only in that in place of a single supply and take-up spool there are provided a plurality of supply spools 282, 284, and 286, and a plurality of take-up spools 288, 290, and 292. All of the take-up spools are actuated from the driving conveyor roll 294 through a series of gears 295 indicated by the dot and dash circles. The gears 296, 298 and 300 on each take-up spool 292, 290, and 288, turn its associated spool through a friction slip drive (not shown). The several strip films S', S'', and S''', are driven at various rates of speed by sprockets 302, 304, and 306, which are actuated by a driving train (not shown) starting from the roller 294. Said driving train is so constructed, in any fashion well known in the art, that the speed of each of the sprockets 302, 304, 306 can be adjusted to secure a different plane in focus on each of the strips S', S'', S''' in accordance with the formula

$$B = A \left(\frac{G}{E} - 1 \right)$$

In addition to the adjustable lead mask 308 on top of the light-proof housing 310 for the film system which serves to define an aperture 311 for governing the exposure time of the top film S', I may also provide a separate adjustable lead mask 312, 314 for each of the other strip films S'', S'''. As indicated in Fig. 8, the masks should be arranged so that successively smaller apertures underlie one another. However, the relative physical position of the strip films S', S'' and S''' does not necessarily correspond to the relative physical position of the planes sectionally radiographed thereon; that is, the top film S' need not have a sectional radiograph of the uppermost plane latently formed therein, but may have a sectional radiograph of a lower plane, whereas the second strip film S'' may take the radiograph of the uppermost plane, since the

plane radiographed on any film is governed by the equation

$$B = A \left(\frac{G}{E} - 1 \right)$$

It will be appreciated that with this construction sectional radiographs of different levels of objects can easily be given different exposures, selected to obtain the best results with various thicknesses, weights and densities of parts at such levels. If all radiographs are to have the same exposure the length of the openings in each mask should be adjusted to be directly proportional to the speed of the film directly under it.

If desired, a plurality of independent linkage systems (not shown), like that described with reference to Figs. 6 and 7, may be employed to impart transverse motion to each set of associated supply and take-up spools, which bears the same ratio to a transverse motion imparted to the conveyor belt that the longitudinal rate of travel of such set bears to the linear rate of travel of the conveyor belt.

Decentered transverse views through the objects, either parallel to the plane of travel of the conveyor belt or at an angle thereto, may be obtained by oppositely offsetting the film system and target and, optionally, by angularly inclining the film.

It will thus be seen that I have described methods and apparatuses which achieve the several objects of this invention and are well adapted to meet the conditions of practical use.

As various possible embodiments, other than those described, might be made of the foregoing invention, and as various changes might be made in the embodiments set forth, it is to be understood that all matter herein set forth and/or shown in the accompanying drawings is to be interpreted as illustrative and not in a limiting sense.

Having thus described my invention, I claim as new and desire to secure by Letters Patent:

1. A method of taking a plane sectional radiograph of an object comprising bodily shifting the object and film along straight lines in parallel planes and in the same direction relative to a stationary X-ray tube at such relative speeds that a point in the plane section to be radiographed and a point in the film sweep past the target of the tube at the same instantaneous angular speed whereby the shadow of each point in said plane section moves at the same instantaneous angular speed as the corresponding point in the film on which said plane section is being radiographed, and the shadows of points outside of the plane section move at instantaneous angular speeds which differ from those of the instantaneous angular speeds of the points in said section and in said film.

2. A method of taking a plane sectional radiograph of an object comprising bodily shifting the object and film in parallel planes and in the same direction relative to a stationary X-ray tube at such relative speeds that

$$B = A \left(\frac{G}{E} - 1 \right)$$

where A is the distance from a plane to be sectionally radiographed to the target of the tube, B the distance from said plane to the film, E the speed of the object at any instant, and G the speed of the film at the same instant whereby the shadow of each point in the plane to be sectionally radiographed moves at the same instantaneous

angular speed as the corresponding point in the film on which said plane is being radiographed, and the shadows of points outside of the plane being sectionally radiographed move at instantaneous angular speeds which differ from those of the instantaneous angular speeds of the points in said plane and in said film.

3. A method of taking a plane sectional radiograph of a series of objects on strip film comprising continuously bodily shifting objects of said series and said strip film in parallel planes and in the same direction relative to a stationary X-ray tube at such relative speeds that

$$B = A \left(\frac{G}{E} - 1 \right)$$

where A is the distance from a plane to be sectionally radiographed to the target of the tube, B the distance from said plane to the film, E the speed of the objects at any instant, and G the speed of the film at the same instant whereby the shadow of each point in each object in the plane to be sectionally radiographed moves at the same instantaneous angular speed as the corresponding point in the film on which said plane is being radiographed, and the shadows of points outside of the plane being sectionally radiographed move at instantaneous angular speeds which differ from those of the instantaneous angular speeds of the points in said section and in said film.

4. A method as set forth in claim 3 wherein at the same time that the film and objects are continuously bodily shifted to and beyond the X-ray tube they are moved laterally back and forth under said tube, the ratio of the last named movement of the film and objects also being

$$B = A \left(\frac{G}{E} - 1 \right)$$

5. A method of simultaneously taking a plurality of plane sectional radiographs of an object comprising bodily shifting the object and a plurality of films in parallel planes and in the same direction relative to a stationary X-ray tube at such relative speeds that

$$B_n = A_n \left(\frac{G_n}{E} - 1 \right)$$

where $A_1 \dots A_n$ are the distances from the planes to be sectionally radiographed to the target of the tube, $B_1 \dots B_n$ the corresponding distances from each of said planes to the corresponding films, E the speed of the object at any instant, and $G_1 \dots G_n$ the corresponding speeds of the films at the same instant whereby the shadow of each point in each plane to be sectionally radiographed moves at the same instantaneous angular speed as the corresponding point in the corresponding film on which said planes are being radiographed, and the shadows of points outside of the planes being sectionally radiographed move at instantaneous angular speeds which differ from those of the instantaneous angular speeds of the points in said sections and in said films.

6. A method of taking a plurality of plane sectional radiographs of each of a series of objects on strip films comprising continuously bodily shifting the objects of said series and said strip films in parallel planes and in the same direction relative to a stationary X-ray tube at such relative speeds that

$$B_n = A_n \left(\frac{G_n}{E} - 1 \right)$$

where $A_1 \dots A_n$ are the distances from the

planes to be sectionally radiographed to the target of the tube, $B_1 \dots B_n$ the corresponding distances from each of said planes to the corresponding films, E the speed of the objects at any instant, and $G_1 \dots G_n$ the corresponding speeds of the films at the same instant whereby the shadow of each point in each object in each plane to be sectionally radiographed moves at the same instantaneous angular speed as the corresponding point in the corresponding film on which said planes are being radiographed, and the shadows of points outside of the planes being sectionally radiographed move at instantaneous angular speeds which differ from those of the instantaneous angular speeds of the points in said sections and in said films.

7. An apparatus for taking a sectional radiograph of an object with an X-ray tube which remains stationary during radiography, said apparatus comprising means to support an object, means to support a film, and means to bodily shift said object-supporting means and said film-supporting means in parallel planes and in the same direction relative to the stationary X-ray tube at such relative speeds that

$$B = A \left(\frac{G}{E} - 1 \right)$$

where A is the distance from a plane to be sectionally radiographed to the target of the tube, B the distance from said plane to the film, E the speed of the object at any instant, and G the speed of the film at the same instant.

8. An apparatus for taking a sectional radiograph of an object with an X-ray tube which remains stationary during radiography, said apparatus comprising means to support an object, means to support a film, and means to bodily shift said object-supporting means and said film-supporting means along any selected one of a plurality of different paths in parallel planes and in the same direction relative to the stationary X-ray tube at such relative speeds that

$$B = A \left(\frac{G}{E} - 1 \right)$$

where A is the distance from a plane to be sectionally radiographed to the target of the tube, B the distance from said plane to the film, E the speed of the object at any instant, and G the speed of the film at the same instant.

9. An apparatus for taking a sectional radiograph of an object with an X-ray tube which remains stationary during radiography, said apparatus comprising means to support an object, means to support a film, and means to bodily shift said object-supporting means and said film-supporting means along straight lines in parallel planes and in the same direction relative to the stationary X-ray tube at such relative speeds that

$$B = A \left(\frac{G}{E} - 1 \right)$$

where A is the distance from a plane to be sectionally radiographed to the target of the tube, B the distance from said plane to the film, E the speed of the object at any instant, and G the speed of the film at the same instant.

10. An apparatus for taking a sectional radiograph of an object with an X-ray tube which remains stationary during radiography, said apparatus comprising means to support an object, means to support a film, and means to bodily shift said object-supporting means and said film-supporting means along curved lines in parallel

planes and in the same direction relative to the stationary X-ray tube at such relative speeds that

$$B = A \left(\frac{G}{E} - 1 \right)$$

where A is the distance from a plane to be sectionally radiographed to the target of the tube, B the distance from said plane to the film, E the speed of the object at any instant, and G the speed of the film at the same instant.

11. An apparatus for taking a plane sectional radiograph of a series of objects with an X-ray tube which remains stationary during radiography, said apparatus comprising a conveyor belt, means to hold a supply of strip film beneath said belt, means to take up said strip film, means to actuate said conveyor belt and take-up means so as to bodily shift the series of objects and strip film in parallel planes and in the same direction relative to the stationary X-ray tube at such relative speeds that

$$B = A \left(\frac{G}{E} - 1 \right)$$

where A is the distance from a plane to be sectionally radiographed to the target of the tube, B the distance from said plane to the film, E the speed of the objects at any instant, and G the speed of the film at the same instant.

12. An apparatus as set forth in claim 11 wherein means is provided for laterally bodily shifting the strip film and conveyor belt back and forth at the same time that they are moved by the actuating means and at the same ratio speeds,

$$B = A \left(\frac{G}{E} - 1 \right)$$

13. An apparatus for simultaneously taking a plurality of plane sectional radiographs of an object with an X-ray tube which remains stationary during radiography, said apparatus comprising means to support an object, a plurality of means each of which supports a different film, and means to bodily shift said object-supporting means and each of said film-supporting means in parallel planes and in the same direction relative to the stationary X-ray tube at such relative speeds that

$$B_n = A_n \left(\frac{G_n}{E} - 1 \right)$$

where A₁ . . . A_n are the distances from the planes to be sectionally radiographed to the target of the tube, B₁ . . . B_n the corresponding distances from each of said planes to the corresponding films, E the speed of the object at any instant, and G₁ . . . G_n the corresponding speeds of the films at the same instant.

14. An apparatus for taking a plurality of plane sectional radiographs of each of a series of objects with an X-ray tube which remains stationary dur-

ing radiography, said apparatus comprising a conveyor belt, a plurality of means each of which holds a separate supply of strip film beneath said belt, a plurality of separate means each of which takes up a different strip film, means to actuate said conveyor belt and take-up means so as to bodily shift the series of objects and strip films in parallel planes and in the same direction relative to the stationary X-ray tube at such relative speeds that

$$B_n = A_n \left(\frac{G_n}{E} - 1 \right)$$

where A₁ . . . A_n are the distances from the planes to be sectionally radiographed to the target of the tube, B₁ . . . B_n the corresponding distances from each of said planes to the corresponding films, E the speed of the objects at any instant, and G₁ . . . G_n the corresponding speeds of the films at the same instant.

15. An apparatus for taking plane sectional radiographs of a series of objects on film with an X-ray tube which remains stationary during radiography, said apparatus comprising means to support said objects between film and tube and means to continuously bodily shift said object supporting means and film in parallel planes and in the same direction through the field of radiation of the stationary X-ray tube at such relative speeds that

$$B = A \left(\frac{G}{E} - 1 \right)$$

where A is the distance from a plane to be sectionally radiographed to the target of the tube, B the distance from said plane to the film, E the speed of the objects at any instant, and G the speed of the film at the same instant.

16. An apparatus for taking a plurality of plane sectional radiographs of each of a series of objects on underlying films with an X-ray tube which remains stationary during radiography, said apparatus comprising means to support said objects between the uppermost film and the tube and means to continuously bodily shift said object supporting means and films in parallel planes and in the same direction through the field of radiation of the stationary X-ray tube at such relative speeds that

$$B_n = A_n \left(\frac{G_n}{E} - 1 \right)$$

where A₁ . . . A_n are the distances from the planes to be sectionally radiographed to the target of the tube, B₁ . . . B_n the corresponding distances from each of said planes to the corresponding films, E the speed of the objects at any instant, and G₁ . . . G_n the corresponding speeds of the films at the same instant.

JEAN KIEFFER.
